US00D995555S

(12) **United States Design Patent** (10) Patent No.: **US D995,555 S**
Stroier (45) Date of Patent: **** *Aug. 15, 2023**

- (54) **DISPLAY SCREEN WITH GRAPHICAL USER INTERFACE FOR PRESENTING WEBSITE ANALYTICS**

(71) Applicant: **Siteimprove A/S**, Copenhagen (DK)

(72) Inventor: **Christoffer Lund Stroier**, Copenhagen
(DK)

(73) Assignee: **Siteimprove A/S**, Copenhagen (DK)

(*) Notice: This patent is subject to a terminal disclaimer.

(**) Term: **15 Years**

(21) Appl. No.: 29/771,363

(22) Filed: Feb. 22, 2021

Related U.S. Application Data

- (63) Continuation of application No. 29/621,701, filed on Oct. 10, 2017, now Pat. No. Des. 911,352.

(57) **CLAIM**

The ornamental design for a display screen with graphical user interface for presenting website analytics, as shown and described.

DESCRIPTION

The FIGURE is a front view of a display screen with a graphical user interface for presenting website analytics. The broken lines showing a display screen and elements of the graphical user interface illustrate portions of the article, and form no part of the claimed design.

1 Claim, 1 Drawing Sheet
